UNITED STATES PATENT OFFICE.

ANDREW W. FOOTE, OF CLEVELAND, OHIO.

PISTON-TURNING MACHINE.

1,095,322.

Specification of Letters Patent.

Patented May 5, 1914.

Application filed January 9, 1913. Serial No. 740,970.

To all whom it may concern:

Be it known that I, ANDREW W. FOOTE, a citizen of the United States, and a resident of Cleveland, county of Cuyahoga, and State 5 of Ohio, have invented a new and useful Improvement in Piston-Turning Machines, of which the following is a specification, the principle of the invention being herein explained and the best mode in which I have 10 contemplated applying that principle, so as to distinguish it from other inventions.

The subject of the present invention is a machine adapted to operate on piston members turning up the periphery of the pistons 15 and simultaneously smoothing the upper surface of the same. This action is secured by means of a tool held in a reciprocating slide and other tools held in a swinging arm, the movement of the two tools being in directions at substantially right angles. A third operation performed is the forming 20 of the grooves in the periphery of the pistons for the packing rings. Means are provided for thus operating the tools in synchronism, suitable driving members being connected to operate both tool bearing parts. While the tool bearing parts are operated in synchronism, it will be understood that the 25 cutting operations of the various tools need not necessarily occur simultaneously, the exact time of each operation depending upon the adjustment of the tools.

The machine has been especially designed to secure the greatest possible simplicity and 30 compactness of construction, and to this end the various units, which will preferably be connected in one machine, are disposed vertically, thus saving considerable floor space, and permitting one operator to conveniently 35 control and oversee the operation of the several units. It is not intended to limit the use of the present machine to the forming of pistons, as it may of course, without material change, be adapted to operate on various 40 materials which must be machined on two transversely disposed surfaces. The number of units which make up each machine is also of little consequence so long as each unit embodies the principles of construction and operation which constitute the 45 vital elements of the invention.

To the accomplishment of the foregoing and related ends, said invention, then, consists of the means hereinafter fully described, and 50 particularly pointed out in the claims.

The annexed drawings and the following

description set forth in detail certain mechanism embodying the invention, such disclosed means constituting, however, but one of various mechanical forms in which the principle of the invention may be used. 60

In said annexed drawings: Figure 1 is a front elevation of a machine consisting of a plurality of connected units; Fig. 2 is an end elevation of a single unit; Fig. 3 is a central vertical section through the work spindle taken on the line 3—3 in Fig. 2; Fig. 4 is a central vertical section on the line 4—4 in Fig. 1; Fig. 5 is a horizontal section on the line 5—5 in Fig. 2; Fig. 6 is a vertical section on the line 6—6 in Fig. 1 showing the automatic drive-releasing mechanism; Fig. 7 is a horizontal section on the line 7—7 in Fig. 4; Fig. 8 is a similar view on the line 8—8 in Fig. 4; Fig. 9 is a horizontal section on the line 9—9 in Fig. 3; Fig. 10 is a similar section on the line 10—10 in Fig. 3; and Fig. 11 is a side elevation of a detail of construction. 70

In Fig. 1 the general construction of the machine will be seen. While it is immaterial how many units are connected to form the finished machine, I have here shown four such units which are mounted upon a single base or frame 1, such units being spaced 80 from each other and being totally disconnected except so far as they may be said to be connected by being driven from a single main driving shaft 2. The driving shaft 2 is suitably journaled in the two ends of the frame, being disposed horizontally, and at one end it is provided with pulleys 3 and 4 of different sizes for the purpose of securing drives of various speeds. A bracket 5 attached to the frame serves to support the 85 extending end of the main shaft which carries such pulleys. 90

Turning then to the features of the mechanism which constitute the present invention, it will only be necessary to describe in full a single unit, as the units are of course identical in construction and operation. Upon the frame there is mounted a roughly cylindrical casting 6 open at the rear which houses an intermediate driving shaft connected to actuate the tool-carrying members of the device, and is adapted to provide a support for such tool-carrying members themselves. 100

A tubular spindle 8 is vertically mounted in the frame in bushings 9 and 10, the first 110 of these 9 being tapered and secured in posi-

tion by a nut 11, while the second bushing 10 is held within a tubular extension 12 of the main frame, being secured thereto by any suitable means such as set screws 13. 5 Supported upon the bushing 10 is a ball bearing 140 adapted to receive the vertical thrust of a worm gear 14 keyed to the spindle 8. Below the bearing 10 there is keyed to the spindle a bevel gear 15 held in position by nuts 16 and 17 engaging the threaded portion of the spindle. The lower end of the spindle is engaged by an apertured block 18 bearing a plurality of pivoted bell crank clutch arms or jaws 19. These arms 10 are adapted, when moved outward, to contact and move a disk 20 attached to a clutch rod 21 extending upwardly through the spindle. The outward movement of the arms is secured by the raising of a cone 22 15 attached to spaced collars 23 engaged by a yoke 24 pinned to a vertically sliding rod 25 mounted in the frame. Such rod 25 is formed with a rack 26 engaged and operated by a gear 27 attached to a shaft 28 disposed horizontally in the frame and extending 20 through the front of the same. Operating handles 29 are attached to said shaft exteriorly of the frame. A spring 141 is disposed about the clutch rod 21 between the 25 disk 20 and a plate 143 attached to the collar 23 and serves to return the rod to its upper or disengaged position. Mounted on the top of the spindle is a chuck plate 30 against which the work 31, shown as a piston casting, is held by means of a bar 32 entering oppositely disposed apertures in the piston and pivotally engaged by a socket 33 30 adjustably attached to the clutch rod 21. The action of the clutch brings the work 35 into operative engagement with the chuck plate so that it will be rotated therewith. The precise form of chuck and the operation of the same are of little importance in the present connection as any suitable means 40 may be employed.

Mounted on and attached to the bearing 9 is a flanged bearing 34 formed in cone-shape externally, and over this is attached a dust cap 35 attached to the spindle by set 45 screws 36, the cap rotating with the spindle. The introduction into the bearings of dust, dirt and metal shavings is thus absolutely prevented as will be seen, while the parts just described are readily removable when it is necessary to take out the spindle or replace the bushings.

The drive for the spindle is best shown in Figs. 3 and 5, the drive shaft being provided with a worm 40 which is rotatably mounted 50 thereon against a fixed bearing 41, the worm being provided with a serrated clutch face 42 adapted to be engaged by a rotatably fixed but slidably complementary clutch member 43 controlled by the usual jaws or 55 fingers 44 which will be operated by means

to be hereinafter described. Ball bearings 145 are disposed at suitable points along the main shaft to reduce to a minimum the friction from the longitudinal thrust caused by the pressure on the worm. The worm when 70 in engagement with the fixed clutch member is adapted to be rotated by the driving shaft and drives the worm gear 14 which is fixedly mounted on the tubular work spindle. In this manner the work is driven from 75 the main driving shaft although it may be at any time thrown out of gear and rendered inoperative by the operation of the clutch members 42. The various other parts of the mechanism are conveniently driven from the 80 spindle, as by this arrangement the disengagement of a single clutch member renders all of the mechanism inoperative.

The bevel gear 15 upon the lower end of the sleeve engages a similar complementary bevel gear 45 fixedly attached to the end of a horizontal shaft 46 provided at its other end with a fixed worm member 47 engaging a gear 48 mounted upon a vertical driving shaft 49 housed at its upper end in the vertical cylindrical casting 6. The gear 48 is 85 rotatable on this vertical shaft and is fixed to the shaft by means of a slidable but rotatably fixed clutch 50 which may, of course, be of any suitable construction and need not 90 be described in detail, this second clutch being operated by a lever 51 which is attached to the end of an oscillatory shaft 52 extending through the front of the frame where it is attached to a hand lever 53 as shown. 100 The purpose of this clutch mechanism will be hereinafter fully explained.

The vertical shaft 49 extends upwardly through the cylinder and is provided at its upper end with two fixed gears 54 and 55 105 which are here shown as having different numbers of teeth adapting them to engage two complementary gears 56 and 57 respectively, attached to a second vertical shaft 58 rotatably mounted in the cylinder. The 110 use of two driving gears having different numbers of teeth provides a steady and accurate drive and reduces to a great extent the wear on the teeth of either gear, thereby preventing any backlash between the teeth, 115 and any inaccuracy in the timing of the driven shaft. The second vertical shaft is rotatably mounted in the cylinder as before mentioned, being housed in suitable bearings 60 and 61, ball bearings 150 and 151 being 120 also provided. The lower portion of the shaft is threaded adapting it to adjustably engage a cylindrical cam 63 which may be attached to the shaft by keys 64 when it is adjusted to the proper position. 125 Upon the outer face of the cylinder there is engaged and reciprocably mounted upon machined guides 104 a tool slide 70 which is adapted to be reciprocated in a vertical direction by means of the cylindrical cam al- 130

ready referred to. A vertical slot 71 is provided in the face of the cylinder through which extends a bearing pin 72 attached to the tool slide and engaged in the slot 73 in the cam. The slot in the cam is formed as shown in Fig. 4 and the operation by which the tool slide will be reciprocated will be readily understood from this figure. It will be seen that one complete revolution of the 5 vertical shaft 58 gives to the tool slide a downward and a return movement, the operation of the tool slide being absolutely and positively controlled by the cylindrical cam, and being made to perform a complete cycle 10 of movement for each complete revolution of the cam. A counterweight 160 for the tool slide is provided and is connected thereto by a cable 161 operating over two grooved pulleys 162 mounted on the side of the cylindrical casting. The cable is attached to the 15 slide by means of a threaded pin 163 engaged therein and operating in a slot 164 in the outer face of the cylinder, and to the weight by means of a hook 165.

20 On the vertical shaft 58, adjacent to the upper end of the same there is keyed a plate cam 75. In suitable brackets 76 extending laterally from the cylinder there is mounted a vertical oscillatory shaft 77 provided at 25 its upper end with a contact arm 78 having fixed at its upper end a flanged stud 79 adapted to be contacted and operated by the plate cam on the vertical shaft 58. The oscillatory shaft is provided at its lower end 30 with a second or tool-bearing arm 80 adapted to receive a suitable cutting tool 81. The tool 81 is adapted to operate on a vertical surface upon the inward swinging of the arm 80. In the tool bearing arm 80 there 35 are also mounted a plurality of tools 168 adapted at a certain point in the movement of the arm to operate laterally on the work. These are so positioned, however, that they do not operate until after the surfacing of 40 the sides of the work by the tool carried by the slide, being adapted to cut the recesses in the pistons which are to receive the packing rings. The construction of the plate cam is best shown in Fig. 8, and it will be 45 seen that when the vertical shaft 58 is rotating in a clockwise direction (from the viewpoint taken in Figs. 7 and 8) the tool arm will be swung inwardly or in a clockwise direction toward the work spindle 50 through the major portion of the revolution at a very slow speed, and at a certain point in the revolution the highest point of the cam will pass the stud 79 on the arm. Suitable resilient means, here shown as a coiled 55 spring 83 suitably attached to the cylinder and to the bearing arm are provided for rapidly returning the oscillatory shaft to its normal position at this point in the revolution of the shaft 58.

60 Upon the upper end of the shaft 58 there

is fixed a bevel gear 90 engaged by a second bevel gear 91 attached to a short horizontal shaft 92 extending through, and borne by, a short projection 93 on the top of the cylindrical casting, the shaft terminating in a 65 square head 94 as shown in Fig. 4. The use of these means is extremely convenient when, through some accident or flaw in the casting, the material being operated upon is broken, in which case it is undesirable, and 70 even unsafe to the machine, to permit the work to be further operated upon, as it is possible that some of the mechanism or tools will be broken or damaged by the operation upon a broken casting. Should, 75 therefore, a piece of material become broken, it is only necessary to stop the machine by turning the hand lever 53 which operates the second clutch 50 controlling the driving engagement of the gear at the lower end of 80 the vertical driving shaft 49. When this lever is thrown the gear is disengaged from the shaft and further movement of both of the tool bearing members is at once stopped. It is then possible to unclamp the material 85 from the work spindle by rotating the handles 29, although it will be seen that this operation is not necessary to the returning of the tool members to the starting position, and by rotating the short shaft 92 mounted 90 in the head of the cylinder the two cams may be returned to their normal or starting position regardless of the point of operation which they had attained at the time of the breakage. This mechanism is extremely 95 important in machines of the present type where a number of units are connected to be driven by a single shaft, as should a break occur in one of the castings it is not economical to stop the entire machine while 100 the broken part is being removed. With the mechanism just described it is possible to remove a single casting and yet not interfere with the operation of the other units of the machine. 105

The tool slide 70 and the tool arm 80 are best shown in Figs. 1, 2 and 4. The tool slide is provided at its lower portion with a pivotally mounted tool bearing arm or lever 96, and a spring 97 is interposed between 110 the slide and one end of this arm for the purpose of normally retaining the tool holding part 98 of the arm in contact with the face of the slide. The usual means may be provided for adjusting and attaching the 115 cutting tool 99 to the tool arm, and such means form of course no part of the present invention and hence need not be described in detail. It is only necessary to say that the tool is held horizontally in the tool arm and 120 is adapted to operate upon a vertical surface as the slide is reciprocated. A rod 100 is borne vertically on the face of the tool slide and between the outer face of the slide 125 and the tool arm, the slide being apertured 130

at the projections 107 and 108 to receive the rod. With the faces of the arm and slide in contact the cutting tool will be in position to operate upon the material on the spindle. 5 The rod is provided at its lower end with a recessed portion 101, the recess terminating at its lower end in a beveled face 102 which is adapted, upon relative movement of the rod and arm, to engage against the lower 10 edge of the tool arm, thus slightly oscillating the arm and swinging the cutting tool out of engagement with the work. At the lowest point of the downward movement of the slide, the rod, which is of course in its 15 normal or lowest position, where it is held by a disk 103 attached to it and in contact with the top of one of the machined guides 104 on which the slide moves, is engaged at its tapered or beveled portion 102 by the tool 20 arm, thus forcing the tool outwardly from the slide and disengaging the tool from the work. The action of the beveled face on the rod is to wedge itself tightly between the tool arm and the slide, thus retaining the 25 rod in this position during the upward movement of the slide and preventing any engagement or even contact between the cutting tool and the work. When the slide reaches its upper position the upper end of the rod 30 engages the projection 105 at the upper end of the cylinder and forces the rod to its lower position, at which time the spring 97 will return the tool arm into contact with the slide, thus preparing the tool for the 35 downward movement of the slide by placing it in its operative position. The importance of these means will of course be seen, as it is necessary that the machined face of the work is not marred or scratched by the action 40 of the cutting tool during the return movement of the slide.

It is desirable to provide means which will automatically operate to release the drive from the cam shaft 58 upon the completion of each cycle, in order that new material may be inserted before the next operation of the tool bearing arm and slide. The mechanism which I have designed for this purpose is entirely automatic in character, 45 it being only necessary to manually set the means upon the beginning of each new cycle. Extending upwardly from the frame is a bracket 110 adapted to suitably journal a short horizontal shaft 111 mounted parallel 50 with the face of the tool slide and bearing at its right end a rectangular portion 112 which is adapted to be received in a knock-off member or lever 113 which is provided with a longitudinal and substantially rectangular 55 slot 114 in which is carried a coil spring 116 adapted to normally retain the knock-off member with its engaging end 117 at the maximum possible distance from the horizontal shaft 111. In other words, the knock-off 60 member is normally retained in such a

position that it will be engaged by a suitable contacting face or lug 118 carried by the tool slide. A pin 115 fixed in the engaging end 117 of the lever 113 is provided to be contacted by the lug 118 on the tool slide. 70 At the other end of the shaft there is attached a disk 120 upon which there is eccentrically mounted a rod 121 extending downwardly therefrom, such rod being provided with an indentation forming a contacting face 122 which is adapted to receive a pin 123 mounted at a suitable point upon the face of the disk. The rod is pivotally attached at its lower end to a lever 124 pivotally attached to a pin 166 mounted on the bracket 80 110, the lever being pivotally attached at its outer end to a link 125 having its lower end formed into a yoke 126 which engages a horizontally disposed arm 127 connecting with and operating a shaft 128 which bears the clutch member 43 controlling the engagement of the main driving worm 40 to the shaft 2.

The knock-off lever has a handle 129 formed on its outer end, its inner end being rounded, the lever resting normally in the position shown in Fig. 6. The contacting lug 118 attached to the lower part of the tool slide is adapted, upon downward movement of the latter, to strike against the 95 round pin of the extending end of the knock-off lever. Should the knock-off lever not be in the position shown in Fig. 6, that is, should it be slightly nearer the horizontal, the action of the lug will force the lever into position of Fig. 6, at which time the pin 123 on the disk will have been rotated through a portion of a circle, caused of course by a rotation of the horizontal shaft, the pin then engaging the recessed 100 face 122 in the lever which prevents further rotation of the disk except after shearing of the pin or breaking of some of the other parts of the mechanism. The pressure of the lug 118 against the rounded surface 105 of the pin 115 will cause pressure on the lever in a horizontal direction and also in a vertical direction. The vertical pressure is of course resisted by the action of the pin in the recess so that the horizontal pressure will tend to force the lever longitudinally away from the contacting lug as the spring 116 exerts a less pressure than that component of the horizontal pressure on the lever which acts in a direction alined with 115 the center line of the knock-off lever. It will be understood then that downward movement of the slide causes merely a sliding of the knock-off lever without operatively rotating the horizontal shaft to 120 operate the main clutch. Upward movement of the tool slide, however, causes the lug to again engage the knock-off lever but the pressure in this case causes a rotation or swinging of the horizontal shaft which, 130

through the links which have been described in the preceding paragraphs, will actuate the main clutch to disengage the main driving worm from the driving shaft. The lug 5 will be so disposed upon the tool slide relatively to the position of the knock-off lever that the disengagement of the main clutch will occur at the highest point of movement of the tool slide, that is, at the exact point 10 of the completion of the cycle of operations. Before starting the mechanism again the knock-off lever must be manually returned to its normal position (see Fig. 6) which may be done by pulling the lever away 15 from the tool slide until the rounded end will pass the lug and then rotating to the desired position, which engages the main driving clutch members 42 and 43.

Certain details of construction have not been described at length for the reason that in the majority of these cases any suitable and well known means may be provided for carrying out the operation of the parts described. An example of this is the plate 180 which is provided with two downwardly extending tubular portions 181 and 182, in each of which there is provided a bushing, these bushings 60 and 184 being adapted to respectively journal the shafts 58 and 49, the plate itself resting upon a partition 185 in the upper portion of the cylinder. Similarly the particular form of the frame is of little importance in the present connection provided it is adapted to support and properly carry the various operating parts of the mechanism.

The various units which make up an assembled machine may be operated either together or singly, and it is not necessary that the operation of each unit correspond in time to that of any other unit. In fact preferably the reverse will be true in order that one operator may properly and conveniently control the various units. When the main driving shaft is rotating, and it is desired to turn up a piston, the piston is placed upon the chuck plate 30, the piston seating in the circular recess 186 in the plate and being held thereon by the means described and shown in Fig. 3. After the piston member has been properly placed on the chuck plate, it may be locked to rotate with the spindle by turning the handles 29. It will be assumed that the two tool bearing members, the slide and the swinging arm, are at their starting or inoperative position at this time. It is then necessary to rotate the knock-off lever 113 into the position shown in Fig. 6. This operation engages the clutch 43 with the clutch member 42 attached to the main driving worm 40, thus causing rotation of the spindle through the gear 14 and consequently rotation of the piston member which is carried on the chuck plate. The rotation of the spindle

rotates the short horizontal shaft 46 through the bevel gears 14 and 45 and the rotation of this shaft operates the shaft 49 through the gear 48 and worm 47, it being assumed that the clutch 50 is in position to lock the gear 48 to the shaft 49. Rotation of the shaft 49 drives the cam shaft 58 through the gears 54, 55, 56 and 57, thus rotating the cylindrical cam 63 and the plate cam 75. As will be seen from the conformation of the cam members, the cylindrical cam will at once begin to move the tool slide downwardly, and if the tool 99 is properly adjusted it will at once begin to machine the side of the rotating piston, it being fed downwardly continuously through this operation. The plate cam develops very slowly during the first quarter of its revolution, and it will therefore be seen that the tool arm 80 and the tool 81 are not moved into a position where the latter will engage the top of the piston until the tool slide has moved down a considerable distance. At this point, however, the tool 81 will engage the top of the piston and will be fed across to the center of the piston. When the latter point is reached, the highest point of the cam engages the stud 79 and the release of the oscillatory shaft 77 follows, thus rapidly swinging the tool 81 from out of engagement with the top of the piston member by means of the spring 83.

The tools 168 which are similar in construction, but are spaced a certain distance from each other, engage the piston after the tool 99 has machined the upper half of the surface of the piston, the tools 168 then cutting recesses or grooves in the wall of the piston for the purpose of receiving the packing rings to be applied later. The cylindrical cam and the plate cam are so constructed and timed that the tool 99 and the tool slide will have reached their lowest position at the same time that the tool 81 reaches the center of the upper surface of the piston, and the tools 168 reach the desired depth of groove in the wall of the piston. At this point the rod 100 swings the tool bearing arm 98 into a position which removes the tool 99 from engagement with the wall of the piston. The tool carrying arm 80 is simultaneously swung away from the piston, and the tools 81 and 168 are therefore both removed from engagement with the piston. During the return movement of the tool slide the arm 78 is gradually returned toward the tool, as will be readily seen from an inspection of the plate cam 75, but the tool 81 will not be brought into close proximity with the piston until the tool slide has reached the limit of its upward movement, or in other words until a cycle of operations has been completed. As the tool slide reaches its upper position the lug 118 operates the knock-off lever 113 which disen-

gages the main driving clutch 43 from the clutch on the worm 40. The unit is therefore at this time inoperative, and the piston may be removed from the spindle by releasing the chuck by rotating the handles 29, and a new piston inserted when the operation will be repeated.

It is unnecessary to describe the action in case a piston is broken during the operation, as that has been already described. In such an event the lever 53 is rotated, which disengages the driving connection between the shaft 49 and the gear 48, thus stopping the further operation of the two cams and consequently of the tool bearing members. The latter may be returned to their initial positions by operating the short horizontal shaft 92 in the manner previously indicated.

The important features of the invention are the construction of piston turning machines which may be connected to be driven from a single driving shaft, the single units being formed vertically, thus affording an extremely compact construction. A further part of the invention is a synchronized and co-operative movement of a plurality of separately carried tool members driven from a single driving shaft through any suitable means, which are here shown as cams. The advantage of providing an automatic drive releasing mechanism, which may be returned to its engaging position by a single manual movement will be readily seen, as will the advantage of having means for manually releasing the drive in case of breakage of the work or failure of any of the parts of the machine.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination of a vertically disposed work spindle; a vertically movable tool slide; a vertically disposed rotatable shaft; an oscillatory vertical shaft; a tool arm attached to said oscillatory shaft; a second arm attached thereto; a cylindrical cam operatively mounted on said rotatable shaft and adapted to reciprocate said tool slide; a plate cam operatively mounted on said rotatable shaft and adapted to actuate said second arm on said oscillatory shaft, thereby oscillating the latter in one direction, said two cams being formed to synchronously move said tool slide in one direction and to swing said tool arm; a coiled spring attached to said arm and adapted to return said tool arm to normal position before the return of movement of said tool slide; a tool

carrier pivotally mounted on said slide about a vertical axis; resilient means normally retaining said carrier in its work engaging position; and means operable upon movement of said slide and adapted to swing said carrier out of engagement with the work during the return movement of said slide.

2. In mechanism of the character described, the combination of a vertically disposed work spindle; a vertically movable tool slide; a vertically disposed rotatable shaft; an oscillatory vertical shaft; a tool arm attached to said oscillatory shaft; a second arm attached thereto; a cylindrical cam operatively mounted on said rotatable shaft and adapted to reciprocate said tool slide; a plate cam operatively mounted on said rotatable shaft and adapted to actuate said second arm on said oscillatory shaft, thereby oscillating the latter in one direction, said two cams being formed to synchronously move said tool slide in one direction and to swing said tool arm; a coiled spring attached to said arm and adapted to return said tool arm to normal position before the return movement of said tool slide; a tool carrier pivotally mounted on said slide about a vertical axis; a rod slidably mounted in said tool slide and being provided with a tapered portion adapted to engage and to swing said carrier out of engagement with the work; and a stop adapted to be contacted by said rod upon movement of said slide, whereby the movement of said slide brings such tapered portion of said rod into engagement with said carrier, thereby swinging the same out of engagement with the work.

3. In mechanism of the character described, the combination of a vertically disposed work spindle; a vertically movable tool slide; a vertically disposed rotatable shaft; an oscillatory vertical shaft; a tool arm attached to said oscillatory shaft; a second arm attached thereto; a cylindrical cam operatively mounted on said rotatable shaft and adapted to reciprocate said tool slide; a plate cam operatively mounted on said rotatable shaft and adapted to actuate said second arm on said oscillatory shaft, thereby oscillating the latter in one direction, said two cams being formed to synchronously move said tool slide in one direction and to swing said tool arm; a coiled spring attached to said arm and adapted to return said tool arm to normal position before the return movement of said tool slide; a tool carrier pivotally mounted on said slide about a vertical axis; a rod slidably mounted in said tool slide and being provided with a tapered portion adapted to engage and to swing said carrier out of engagement with the work; and two spaced stops adapted to be contacted by said rod upon movement of said slide, whereby one movement of said slide brings

such tapered portion of said rod into engagement with said carrier, thereby swinging the same out of engagement with the work, and the return movement of said slide 5 releases such tapered portion of said rod from engagement with said carrier, thereby permitting the latter to return to its work engaging position.

4. In mechanism of the character described, the combination of a main driving shaft; a worm rotatably mounted thereon; means adapted to connect said worm to said shaft to be driven thereby; a work spindle adapted to be driven by said worm; a reciprocably mounted tool slide; means driven from said spindle and adapted to reciprocate said slide; a contacting face formed on said slide; a pivotally mounted lever adapted to be engaged and actuated by said contacting 20 face upon the completion of a cycle by said slide; and means operated by said lever, said means being connected to said first-named means for connecting said worm to said shaft, whereby the latter is disengaged, stopping the operation of said mechanism.

5. In mechanism of the character described, the combination of a main driving shaft; a worm rotatably mounted thereon; a clutch adapted when operated to operatively connect said worm to said shaft; a work spindle adapted to be driven by said worm; a vertically reciprocable tool slide; means driven by said spindle and adapted to reciprocate said slide; a laterally extending 35 lug attached to said tool slide; a horizontal shaft mounted parallel with said slide; a lever fixed to rotate with said shaft, said lever being transversely slidable on said shaft; means connecting said horizontal shaft and said clutch, whereby operation of said lever causes disengagement of said clutch, said lever extending into the path of movement of said lug at an angle to the 40 shaft and said clutch, whereby operation of said lever causes disengagement of said clutch, said lever extending into the path of movement of said lug at an angle to the

same when said clutch is engaged; and means restraining rotation of said lever 45 when contacted by said lug upon downward movement of said tool slide, whereby said lever slides transversely of said shaft.

6. In mechanism of the character described, the combination of a main driving shaft; a worm rotatably mounted thereon; a clutch adapted when operated to operatively connect said worm to said shaft; a work spindle adapted to be driven by said worm; a vertically reciprocable tool slide; 55 means driven by said spindle and adapted to reciprocate said slide; a laterally extending lug attached to said tool slide; a horizontal shaft mounted parallel with said slide; a lever fixed to rotate with said shaft, said 60 lever being transversely slidable on said shaft; means connecting said horizontal shaft and said clutch, whereby operation of said lever causes disengagement of said clutch, said lever extending into the path of movement of said lug at an angle to the same when said clutch is engaged; a disk attached to said horizontal shaft; a link pivotally attached eccentrically to said disk, said lever being provided with a transversely disposed 65 contacting face; a pin mounted on said disk and adapted to be moved into engagement with such contacting face upon contact of said lug with said lever upon downward movement of said slide, thereby restraining 70 rotation of said horizontal shaft and causing said lever to slide from beneath said lug, the latter being adapted to rotate said lever, thereby disengaging said clutch, upon upward movement of said slide. 75

Signed by me, this 7th day of January, 1913.
